UNITED STATES PATENT OFFICE.

FRED MACEY, OF GRAND RAPIDS, MICHIGAN.

DESIGN FOR A GARMENT-HOOK.

SPECIFICATION forming part of Design No. 30,464, dated April 4, 1899.

Application filed December 19, 1898. Serial No. 699,771. Term of patent 14 years.

To all whom it may concern:

Be it known that I, FRED MACEY, a citizen of the United States, residing at the city of Grand Rapids, in the county of Kent and State 5 of Michigan, have invented and produced a new and original Design for a Garment-Hook, of which the following is a full, clear, and exact specification.

My invention relates to a new and original 10 design for garment-hooks, and is illustrated in the accompanying drawings, wherein—

Figure 1 is a perspective view, and Fig. 2 a plan view thereof.

The leading feature of my design consists 15 of a garment-hook having a body formed with an eye at its end and having a bend or hook formation at its other end, with open or eye-like formations projecting laterally from the body intermediate the ends and an upwardly- 20 curved portion beneath the hook-like formation and transversely in line with and between the lateral eyes.

In the said drawings the reference-numeral 1 indicates the body, and the reference-letter

C the eye-like formation at one end of said 25 body.

The reference-letter E indicates the curved or hook formation at the opposite end of the body, and the reference-letters B and D the lateral eye-like formations intermediate the 30 ends of the body.

A indicates the bent portion, curving upwardly toward the hook-like formation and arranged transversely in line with and between the eye-like formations B and D. 35

My design presents a garment-hook of novel and distinguishing appearance.

Having thus described my invention, what I claim is—

The design for a garment-hook herein shown 40 and described.

In testimony whereof I have hereunto set my hand in presence of two subscribing witnesses.

FRED MACEY.

Witnesses:

EDWARD TAGGART,
CHRISTOPHER HONDELINK.
